UNITED STATES PATENT OFFICE.

HERMAN FREDERICK NEHR, OF NEW YORK, N. Y.

LUNA FOR HOLDING THE HOST.

No. 810,217.

Specification of Letters Patent.

Patented Jan. 16, 1906.

Application filed August 25, 1905. Serial No. 275,849.

To all whom it may concern:

Be it known that I, HERMAN FREDERICK NEHR, a citizen of the United States, and a resident of the city of New York, borough of Brooklyn, in the county of Kings and State of New York, have invented a new and Improved Luna for Holding the Host, of which the following is a full, clear, and exact description.

10 The purpose of the invention is to construct a luna in which the host is visible from the front and the back and wherein when the luna is opened the host or wafer will be so supported on the back member of the luna 15 that it can be readily removed by the officiating divine.

10 A further purpose of the invention is to provide a simple and effective lock or latch for holding the hinged portion of the luna so 20 surely closed, the said lock or latch being so constructed that it can be operated with perfect ease by the hand of the priest exclusive of those fingers purified to receive the host, and, further, to provide means operating in 25 conjunction with the lock or latch whereby through the medium of the same fingers of the same hand the luna may be quickly and conveniently opened and ready access be obtained to the host.

30 A further purpose of the invention is to so construct the interior of a luna that there will be no crevices difficult to clean.

35 The invention consists in the novel construction and combination of the several parts, as will be hereinafter fully set forth, and pointed out in the claims.

40 Reference is to be had to the accompanying drawings, forming a part of this specification, in which similar characters of reference indicate corresponding parts in all the figures.

45 Figure 1 is a front elevation of the luna. Fig. 2 is a rear elevation showing the luna locked in full lines and also showing in dotted lines the lock in open position and the back dropped to deliver the wafer, and Fig. 3 is a vertical section taken practically on the line 3 3 of Fig. 2.

50 The body of the luna consists of two receiving members A and B, between which the host or wafer is placed and held. The front receiving member A consists of the customary crystal disk 10, held in a bezel 11, which bezel is provided at its inner portion with a 55 clamping-band 12 in the form of a ring, the

inner edge 13 of which clamping-ring band is downwardly beveled and meets the inner face of the crystal disk 10, as is shown in Fig. 3, so that there is no possible opportunity for any foreign matter to cling to the inside of 60 the member A, which cannot be readily removed. The said front member A is secured at its lower portion to a pedestal 14, and the said pedestal 14 in its turn is attached to a slide 15, adapted to be received in a suitable socket in the ostensory in connection with which the luna is employed.

65 The back member B of the body portion of the luna is of disk-like formation and is made principally of metal. The forward 70 face of this back member B is dished to a greater or lesser extent, as is shown at 16 in Fig. 3, but its outer or marginal portion is flat, as is shown at 16^a in the same figure. The back member B is adapted to fit snugly in 75 the front member A, being held properly spaced from the crystal 10 of the front member by the said clamping band or ring 12, as is also shown in Fig. 3. An opening 17 is made in the central portion of the back member B 80 of the luna, which opening is preferably circular, and in a suitable channel formed in the wall of this opening 17 a crystal 18 is securely held. At the central portion of said crystal 18 an outwardly-extending knob 19 is secured, the outer face whereof is semispherical, and by means of this knob, which is easily caught by the nail of a finger of the operator, the back member B may be drawn from the front member A when the host or wafer is 85 to be removed. By reason of the peculiar shape of the said back member B of the luna as it is drawn away from the front member A the host is received upon said back member and is supported thereby, the straight edge 90 of the member B enabling the officiating clergyman to readily remove the host therefrom.

95 The back member B of the luna is connected at its lower portion by a hinge 21 to a 100 pedestal 22, which extends up from the slide 15 at the rear of the pedestal 14, as is shown in Figs. 2 and 3, the said back member B when the luna is opened being adapted to drop to a substantially horizontal position 105 at an angle to the front member A, as is shown by dotted lines in Fig. 2.

110 The members A and B of the luna are held closed by means of a latch C. This latch is preferably constructed of spring metal, and it

consists of a front member 23, which is capable of extending up from the slide 15 along the central portion of the back member B to an engagement at its upper end with the 5 knob 19, and the said upper end of the locking member 23 is spoon-shaped, as shown at 15 25, being concaved upon its forward face to receive the convexed outer surface of the knob 19. A handle 24, usually in the form of a scroll, 10 as shown, extends at the rear of the locking member 23 from its bottom to a point near the top, and the locking device C is connected with the slide 15 through the medium of a hinge 26, which hinge permits the said locking 15 20 device C to be carried downward to the right or to the left, as may be found most convenient, and when said locking device reaches a lower horizontal position it is prevented from dropping farther by engagement with an upper side portion of the slide 15, as is indicated by dotted lines in Fig. 2.

Under this construction, supposing the host to be within the luna and the locking device C in locking engagement with the 25 back member B, as shown by positive lines in Figs. 2 and 3, the officiating clergyman can raise the luna and look through the same to ascertain if the wafer is properly in place, which can be done with as much convenience 30 and surety as if the major portion of the back constituted a crystal, as is usual. Then upon holding the slide in one hand and by means of either of the fingers below the purified fingers adapted to receive the host the locking 35 device may be readily carried to one side or the other to release it from the knob 19, and by engaging the knob 19 with any of the fingers employed to remove the locking device the back member B may be drawn open, 40 and if the luna is slightly tilted rearward the host will lie upon the inner face of the back member B, from which it may be removed by the aforesaid purified fingers of the hand of the clergyman.

Having thus described my invention, I 45 claim as new and desire to secure by Letters Patent—

1. In a luna, a stationary front member having a crystal therein, a rear hinged back member constructed mainly of metal but 50 provided with a centrally-located crystal, the inner face of the said rear member being dished except at its margin, which is straight, and a locking device for the hinged member of the luna. 55

2. In a luna, a fixed member having its front composed almost entirely of crystal and provided with an inner locking-band for the crystal the inner edge whereof is inclined downwardly and inwardly to an engagement with the inner face of the crystal, a rear hinged member adapted to be received within the front member, the said rear member being made principally of metal and being provided with a crystal at its central portion, the inner face of the said rear member being dished except at its margin which is straight, and a locking device for said rear member. 60 65

3. In a luna, a fixed front and a hinged rear member, each member being provided with a crystal, the rear member having a button extending outwardly from its rear face, a slide with which both members of the luna are connected, a spring-latch having hinged connection with the said slide, the said latch comprising a locking member having a spoon-shaped upper end adapted to receive the head of the said button, and a rearwardly-extending handle member for the purposes 70 75 described. 80

In testimony whereof I have signed my name to this specification in the presence of two subscribing witnesses.

HERMAN FREDERICK NEHR.
